SAMUEL E. SHEPPARD AND JAMES G. McNALLY, OF ROCHESTER, NEW YORK, ASSIGNEES TO EASTMAN KODAK COMPANY, OF ROCHESTER, NEW YORK, A CORPORATION OF NEW YORK

ANTIABRASION PHOTOGRAPHIC COATING

Application filed February 19, 1929. Serial No. 341,195.

This invention relates to photographic films and plates and more particularly to anti-abrasion coatings therefor.

In connection with many types of photographic materials it is customary to provide an anti-abrasion coating commonly known as an over-coating for the photographic emulsion to prevent or reduce abrasion markings thereon. Gelatin has been widely used for this purpose especially on gelatino-silver halide emulsions, but the insolubility of the dried gelatin is such in the aqueous developing solution that it resists the diffusion of the developer so that the time of developing may be appreciably reduced.

In addition to this property of solubility an over-coating of the material of the present invention, is continuous, glass-clear, highly resistant to abrasion, and strong even when applied as a thin protective film to a photographic emulsion.

In order to illustrate one form in which the invention may be utilized reference is made to the accompanying drawing wherein 1 is a transparent support such as cellulosic material; 2 is a sensitized photographic emulsion such as a gelatino-silver halide emulsion; and 3 is an over-coating or protective film of poly vinyl alcohol or oxy-ethylene to protect the sensitized photographic emulsion against abrasion. This over-coating or protective film may be applied as indicated above. If desired, a coating 4 of gelatin may be applied to the back of the celluloid support to prevent curling.

In accordance with the present invention an over-coating for the emulsion is made from a synthetic product in the form of a continuous, glass-clear, film which is strong and readily soluble in an aqueous developing solution. Reference is made to the accompanying drawing, the single figure of which illustrates in perspective and on an enlarged scale a piece of film involving my invention, an edge of the film being shown in section.

We have found that poly vinyl alcohol or oxy-ethylene as prepared by H. Staudinger (Ber. 59, p. 3069, (1926)) and W. O. Herrmann and W. Haehnel (Ber. 60, p. 1658, (1927)), may be used with advantage to form an anti-abrasion coating. As a specific example of this use, a solution of this material in water at 10% concentration can be coated in known-manner, similar to the coating of starch, sizes, and the like, which protects the emulsion from shearing, stresses, abrasions and the like. Unlike an over-coating of gelatin, an over-coating of poly vinyl alcohol or oxy-ethylene when applied in the manner above described and subsequently dried, dissolves readily in water or the aqueous developing solution and thus does not offer resistance to the diffusion of the de-

veloper so that the time of developing may be appreciably reduced.

In addition to this property of solubility an over-coating of the material of the present invention, is continuous, glass-clear, highly resistant to abrasion, and strong even when applied as a thin protective film to a photographic emulsion.

In order to illustrate one form in which the invention may be utilized reference is made to the accompanying drawing wherein 1 is a transparent support such as cellulosic material; 2 is a sensitized photographic emulsion such as a gelatino-silver halide emulsion; and 3 is an over-coating or protective film of poly vinyl alcohol or oxy-ethylene to protect the sensitized photographic emulsion against abrasion. This over-coating or protective film may be applied as indicated above. If desired, a coating 4 of gelatin may be applied to the back of the celluloid support to prevent curling.

What we claim is:

1. An article of manufacture comprising a transparent support, a layer of sensitized photographic material mounted thereon, and a covering of protective material for said layer containing poly vinyl alcohol.

2. An article of manufacture comprising a transparent support, a layer of sensitized photographic material mounted thereon, and a covering of protective material for said layer formed from a solution in water of poly vinyl alcohol at a concentration of the order of 10%.

Signed at Rochester, New York, this 13th day of February, 1929.

SAMUEL E. SHEPPARD.
JAMES G. McNALLY.
